UNITED STATES PATENT OFFICE.

JAMES A. P. CRISFIELD, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

GAS WASHER-SCRUBBER.

1,261,106.

Specification of Letters Patent.

Patented Apr. 2, 1918.

Application filed September 29, 1916. Serial No. 122,818.

To all whom it may concern:

Be it known that I, JAMES A. P. CRISFIELD, a citizen of the United States, residing at Philadelphia, in the county of Philadelphia and State of Pennsylvania, have invented a certain new and useful Gas Washer-Scrubber, of which the following is a specification.

The principal objects of the present invention are, first, to provide compact, comparatively inexpensive and efficient apparatus for both cooling and scrubbing gas, and second, to provide a combination of parts, constituting a single piece of relatively small apparatus, and adapted more efficiently to perform the functions than relatively large separate cooling and scrubbing appliances, thus saving room or space while obtaining the advantages previously mentioned.

Generally stated, my invention consists in subdividing the interior of the casing of a hydraulic valve into two chambers having communication with each other, and providing a liquid spray and a mechanical scrubbing surface in proximity with the communication between the chambers.

The invention further comprises the improvements to be presently described and finally claimed.

The accompanying drawings illustrate one embodiment of the invention and in them—

Figure 1, is an elevational view principally in section.

Fig. 2 is a top or plan view principally in section, and

Fig. 3, is an elevational view, partly in section, illustrating a detail of construction.

In the drawings 1, is a casing provided with a gas inlet dip pipe 5, and adapted to contain liquid for sealing the same. The dip pipe 5, is shown as of the divided variety, but that is not essential, for an undivided dip pipe may be used. 2, is a stationary mechanical scrubbing surface arranged within the casing. In the embodiment of the invention chosen for illustration this mechanical scrubbing surface consists of a series of angle-shape bars, arranged in parallel relation and projecting from the interior wall of the casing. 3, is a partition, bell or skirt sub-dividing the interior of the casing, into an inner and an outer

chamber and adapted to dip into the liquid contained in the casing sufficiently to prevent the passage of gas under normal operating conditions. 4, is an opening in the wall of the bell, partition or skirt and it constitutes a communication between the inner and outer chambers. This opening 4, confronts the mechanical scrubbing surface 2. 6, is a scrubbing-jet arranged in proximity with the opening 4, and scrubbing surface 2. 7, is an off-take communicating with the outer chamber and arranged opposite the scrubbing surface 2. 8, is a splash-plate for preventing the accidental escape of liquid from the casing 1, through the off-take 7. 9, is an extension of the casing and it communicates with the liquid therein by means of the openings 13 and 14. 10, 11 and 12, constitute an overflow for maintaining an appropriate liquid level in the casing and in the extension 9. 16 and 17, are baffle plates arranged in the outer chamber of the casing and disposed in the line of travel of the gas. 15, is a filling device which may be used, if required, for introducing liquid into the casing. It may be remarked that the casing 1, with its accessories and the dip pipe 5, constitute a hydraulic valve to which is added, so as to cooperate therewith for the practice of the present invention, the parts 2, 3, 4 and 6.

In use the entire gas mixture received, is confined and discharged at relatively high velocity upon the mechanical scrubbing surface 2, in order to remove entrained matter, and the liquid spray 6, cools the entire outgoing stream of crude gas mixture prior to its impingement upon the mechanical scrubbing surface 2. The gas is discharged normally upon or perpendicular to the corrugated or ribbed scrubbing surface 2. The baffle plates 16 and 17, act upon the stream of gas after it leaves the scrubbing surface 2, and while it is on its way to the offtake 7. From the foregoing description it is evident that the entire stream of gas is both cooled and scrubbed or washed in a single piece of compact apparatus, and furthermore it is evident that these operations are efficiently performed. The relative positions of the gas inlet 4 and outlet 7 and the employment of the baffle plates 16 and 17 affords a very lengthy and efficient contact of the gas with the external cooling surface of the casing 1.

It will be obvious to those skilled in the art to which the invention relates that modifications may be made in details of construction and arrangement without departing 5 from the spirit of the invention which is not limited as to such matters or otherwise than as the prior state of the art and the appended claims may require.

What I claim is:

- 10 1. A gas washer scrubber comprising the combination of a hydraulic dip valve casing internally subdivided to constitute communicating gas receiving and discharging chambers and provided with a dip-pipe and 15 adapted to contain liquid for sealing the dip-pipe and chambers, and a liquid spray and a stationary mechanical scrubbing surface operatively arranged in proximity with the communication between the chambers, 20 substantially as described.
2. A gas washer-scrubber comprising the combination of a hydraulic dip valve casing internally subdivided to constitute communicating gas receiving and discharging chambers and provided with a dip-pipe and 25 adapted to contain liquid for sealing the dip-pipe and chambers, and a stationary mechanical scrubbing surface operatively arranged in proximity with the communication 30 between the chambers, substantially as described.
3. A gas washer-scrubber comprising the combination of a hydraulic dip valve casing internally subdivided to constitute communicating gas receiving and discharging chambers and provided with a dip-pipe and 35 adapted to contain liquid for sealing the dip-pipe and chambers, a series of projections arranged in the gas discharging chamber and constituting a stationary mechanical 40 scrubbing surface confronting the com-

munication between the chambers, and a liquid spray in proximity with said communication and coöperating with said surface.

4. A gas washer-scrubber comprising the combination of a hydraulic dip valve casing internally subdivided to constitute communicating gas receiving and discharging chambers and provided with a dip-pipe and 50 adapted to contain liquid for sealing the dip-pipe and chambers, a liquid spray and a stationary mechanical scrubbing surface operatively arranged in proximity with the communication between the chambers, and 55 baffles arranged in the discharging chamber.

5. A gas washer-scrubber comprising the combination of a casing provided with a dip pipe and adapted to contain liquid for sealing the same, a stationary mechanical 60 scrubbing surface within the casing, an apertured partition dipping into the liquid in the casing for confining and discharging at relatively high velocity the entire gas mixture upon said surface to remove entrained matter, and a liquid spray for cooling the entire stream of gas mixture prior to its 65 impingement upon said surface.

6. A gas washer-scrubber comprising the combination of a casing adapted to contain liquid and provided internally with a scrubbing surface, a skirt or bell adapted to dip into the liquid and sub-dividing the interior of the casing into inner and outer chambers and provided with a gas opening confronting the scrubbing surface, a dip pipe arranged in and adapted to discharge gas into the inner chamber, and a gas offtake connected with the outer chamber opposite the scrubbing surface, and a scrubbing jet in 70 proximity with the scrubbing surface.

JAMES A. P. CRISFIELD.
